DESIGN FOR A BASE FOR ELECTRIC FANS OR THE LIKE

Ralph E. Kruck, Springfield, Mass., assignor to
Westinghouse Electric & Manufacturing Com-
pany, a corporation of Pennsylvania

Application August 14, 1937, Serial No. 71,093

Term of patent 7 years

To all whom it may concern:

Be it known that I, Ralph E. Kruck, a citizen
of the United States, residing at Springfield, in
the county of Hampden and State of Massachu-
setts, have invented a new, original, and orna-
mental Design for a Base for Electric Fans or
the like, of which the following is a specification,
reference being had to the accompanying draw-
ing forming part thereof, in which:

Figure 1 is a view in side elevation of the base
showing my new design; and

Figure 2 is a plan view of the base.

I claim:

The ornamental design for a base for electric
fans or the like substantially as shown.

RALPH E. KRUCK.
